CONTRACTILE REEL

Ralph W. Emery, Texas City, Tex.

Application October 22, 1946, Serial No. 704,826

2 Claims. (Cl. 242—114)

1

This invention relates to a discharge reel for yarn, fishing lines, or rolled wire.

It is an object of the present invention to provide a reel for yarn, fishing lines, and wire, which can be constructed of standard stock material, which will be light in weight and easily transportable, and which will be cheap to manufacture.

It is another object of the invention to provide a reel which can be easily loaded with a skein of yarn or wire by having the side legs of the members on which the yarn and wire are supported, such that they can be folded outwardly and toward the center of the reel to permit the insertion of a coil of yarn or wire.

It is another object of the invention to provide a support for a reel which has means by which it can be supported on a flat surface, or by which the reel can be suspended from an overhead structure removed from the floor or surface.

It is another object of the invention to provide a central support for the reel which can be easily attached to and assembled from the supporting member on which the reel is journaled.

According to the invention, the reel is formed of Y-shaped members having a bottom portion and two leg portions. There is a central structure having tubular formation in which the upright portion of the member is extended for attachment thereto. The central member is connected to a shaft which is adapted to be attached to a supporting member for the reel so that the reel can be rotated to dispense yarn or wire. The supporting member is adapted to be supported on a floor or surface, or can be suspended from an overhead structure. One leg of each of the Y-shaped members is connected to its bottom portion so that it can be adjusted outwardly to permit, when all of the leg members are so adjusted, the insertion of a coil of yarn or wire over the portions of the members forming the core of the reel. With the coil once inserted, the leg members are then turned into a vertical plane and tightened, so that they serve to retain the yarn coil upon the reel against axial displacement therefrom.

For a better understanding of the invention, reference may be had to the following detailed description taken in connection with the accompanying drawings, in which:

Figure 1 is a perspective view of a reel support and a reel journaled thereupon and constructed according to the present invention.

Figure 2 is an enlarged transverse cross-sectional view taken through the central supporting structure with the supports of the wire members

2

inserted therein and secured thereto by clamping bolts.

Figure 3 is an enlarged perspective view of the ends of the rod which attaches the reel to the supporting frame.

Figure 4 is a fragmentary view of that portion of the frame which includes the latch for securing the ends of the rod.

Referring now to the figures, 10 represents the main supporting frame on which is journaled a reel 11. The main supporting frame 10 includes horizontal floor support pieces of angle shape, as indicated at 12 and 13, and adapted to rest upon a flat floor surface. To these floor pieces there are extended upwardly uprights 14 and 15 connected together at their upper ends by a top piece 16 having a hook 17 thereon by which the support and its reel can be suspended from an overhead structure.

On the upright members are latch members 18 adapted to receive the ends of a shaft 19 forming a part of the reel 11. This shaft 19, on each of its ends, has an annular recess 21 adapted to receive the latches 18. Because the latch 18 extends into the recess 21, the shaft 19 will be retained against axial displacement relative to the main support 10. To release the shaft, the latch elements 18 are dropped down about their pivots 22 and the reel with the shaft can be separated from the main support 10. When the latches are operated, they make frictional engagement with the sides of the upright members to thereby retain them in raised position.

The shaft 19 has a central structure 23 supported thereon. This central structure 23 may rotate relative to the shaft 19, but is prevented from having too easy rotational movement by the provision of a washer 24 and a cotter pin 25 at one side of the structure 23, and a spring 26 with a washer 27 and a cotter 28 at the opposite side of the structure. The spring 26 will urge the structure against the washer 24 and thus limit its freedom to rotate upon the shaft 19. The shaft 19 may have some rotation relative to the main support 10, and within the latch 18.

The central structure has a plurality of circumferentially spaced tubular spokes 31 into which project sleeves 32 and central shanks 33 of Y-shaped members 34, which serve to support the coil of yarn or wire. The sleeves 32 are tight fitting in the spokes 31 and the shanks 33 are secured to the sleeves 32 by bolt means 35. There are four of these Y-shaped members 34 surrounding the central structure 23. Each of these members is of similar construction. In addition

to the shank portions 33 there is provided a base or yarn or coil-receiving portion 36 and a fixed finger 37 and an adjustable finger 38. The adjustable finger is made a separate part of the Y-member and is flattened at its connecting end, as indicated at 39, to have frictional engagement with a similarly flattened end of portion 36. The two parts are secured together by a wing bolt 41.

When it is desired to add to the reel a coil of yarn or wire, the adjustable fingers 38 are drawn outwardly so that they extend axially of the reel and the coil of yarn or wire is slipped over the end of the same and dropped down into place upon the receiving portion 36 of the Y-shaped members 34. Thereafter the adjustable fingers 38 are extended outwardly and the wing bolt 41 tightened in place. The coil is accordingly prevented from leaving the ends of the reel. With the coil of yarn or wire in place on the reel, the reel is supposedly raised and attachment made of its rods 19 to the latch elements 18 on the main support 10. Thereafter, wire or yarn can be withdrawn from the reel and it will rotate upon the support 10.

While various changes may be made in the details of construction, it will be apparent that such changes will be within the spirit and scope of the present invention as defined by the appended claims.

I claim:

1. A reeling device comprising a frame having spaced fixed standards, a reel shaft extending between said standards, means supporting said shaft on said standards, and a reel comprising a hub mounted on an intermediate part of said shaft between said standards, said hub having a plurality of radial tubular spokes extending therefrom, shanks removably inserted and secured in said tubular spokes, cross arms secured to the radially outward ends of said shanks at points intermediate the ends of said cross arms whereby substantial portions of the length of said cross arms extend on opposite sides of said shanks, fixed radially extending fingers on one end of said cross arms, adjustable normally radially extending fingers on the opposite ends of said cross arms, and combined pivot and clamping means mounting said adjustable fingers on said cross arms, said pivot and clamping means being adapted to be loosened to permit said adjustable fingers to be pivoted from their normal radial relation to said cross arms into axial aligned relation with said cross arms, whereby a coil can be installed on or removed from the reel cross arms, and means removably mounting said reel shaft on said

standards comprising latches pivoted on said standards, bearing openings in the standards in which end portions of said reel shaft can rotatably rest with said latches closing said bearing openings to retain the reel shaft therein.

2. A reeling device comprising a frame having spaced fixed standards, a reel shaft extending between said standards, means supporting said shaft on said standards, and a reel comprising a hub mounted on an intermediate part of said shaft between said standards, said hub having a plurality of radial tubular spokes extending therefrom, shanks removably inserted and secured in said tubular spokes, cross arms secured to the radially outward ends of said shanks at points intermediate the ends of said cross arms whereby substantial portions of the length of said cross arms extend on opposite sides of said shanks, fixed radially extending fingers on one end of said cross arms, adjustable normally radially extending fingers on the opposite ends of said cross arms, and combined pivot and clamping means mounting said adjustable fingers on said cross arms, said pivot and clamping means being adapted to be loosened to permit said adjustable fingers to be pivoted from their normal radial relation to said cross arms into axial aligned relation with said cross arms, whereby a coil can be installed on or removed from the reel cross arms, and means removably mounting said reel shaft on said standards comprising latches pivoted on said standards, bearing openings in the standards in which end portions of said reel shaft can rotatably rest with said latches closing said bearing openings to retain the reel shaft therein, said end portions of the reel shaft being formed with circumferential grooves in which portions of said latches engage in their closed positions to prevent axial displacement of said reel shaft relative to said support.
